MERCANDISE DISPLAY ASSEMBLY

Edward M. Levy, Evanston, Ill., assignor to Reflecto-Hardware Corporation, Chicago, Ill., a corporation of Illinois

Application December 28, 1956, Serial No. 631,214

12 Claims. (Cl. 211—148)

The present invention relates to merchandising devices and more particularly to improvements in merchandise display equipment of a type especially suitable for use in retail stores and the like where it is important to display goods in an attractive manner.

Most modern retail store owners or managers are fully aware of the fact that the volume of sales of the various individual items in their inventories usually can be increased materially when each type of merchandise is displayed to its greatest advantage. Because most stores now sell a great variety of different types of items, however, many retail establishments, and particularly the small ones, have not been able in the past to purchase the many types of special display stands, racks and shelves that would heretofore have been necessary to present the different kinds of merchandise in the most attractive manner. Since such racks, stands and shelves have heretofore been of a more or less fixed or permanent nature, and in many instances have been custom-built and virtually incapable of modification, many store owners have thought special display fixtures to be too expensive to be practical and have adhered to the old counter-and-shelf arrangement for nearly all of their smaller goods, with the result that the goods have not been adequately displayed and their places of business in many cases have taken on the drab atmosphere that results when arrangements of goods cannot be varied from time to time.

The principal object of the present invention is to provide a new and inexpensive merchandise display assembly that has a minimum number of parts, all of which may easily be mass produced and substantially all of which are interchangeable and so constructed that a great variety of merchandise display arrangements may be made with one of the assemblies. The different arrangements may be easily and selectively made on the assembly at the place of its use—and all at the selection of the manager of the store or department in which the assembly is installed. As will later become apparent, the assembly comprises a plurality of upright structural members which may be supported in any desired or convenient manner at any location in a store, and upon which a plurality of readily interchangeable panels of novel construction are adapted to be quickly mounted in any of a great variety of arrangements so as to provide attractive vertical background walls or elements for the display of merchandise, horizontal shelves, or diagonally arranged shelves of different slopes—or any combination of these arrangements that may be desired in order best to display the particular merchandise under consideration. Other objects of the invention include the novel manner in which the panels are removably mounted in the position just mentioned, as a result of which the assembly may be changed very quickly from one arrangement to another. The assembly thus has a quality of universal adaption which makes it useful in stores of different kinds and in different departments within the same store.

These and other objects and advantages of the present

2

invention will be apparent from the following description of a preferred embodiment thereof, taken with the accompanying drawings, wherein:

Fig. 1 is a perspective view of the front side of one form of merchandise display assembly constructed in accordance with the present invention, certain interchangeable panels of the structure being selectively arranged to serve as diagonally arranged shelves, and other panels being arranged to provide a vertical background wall for merchandise and a horizontally arranged shelf therebeneath;

Fig. 2 is a fragmentary cross-sectional view taken on an enlarged scale substantially along the line 2—2 in Fig. 1 to show the manner in which the opposite ends of the horizontal shelf are removably supported upon the upright structural members of the display assembly;

Fig. 3 is a partial view in perspective taken from the rear of the display assembly, with the panels of the display assembly being shown in a different arrangement;

Fig. 4 is a fragmentary cross-sectional view on an enlarged scale taken substantially along the line 4—4 in Fig. 3 to illustrate the manner in which the diagonally arranged shelf panels and the vertically suspended merchandise background panels are removably secured upon the upright structural members of the display assembly;

Fig. 5 is a fragmentary elevational view of a portion of the assembly taken substantially along the line 5—5 in Fig. 4;

Fig. 6 is an enlarged fragmentary elevational view taken from the front side of a merchandise supporting hook removably secured upon the front side of the vertical background panel shown in Fig. 3; and

Fig. 7 is a vertical cross-sectional view of the base portion of the merchandise supporting hook of Fig. 6, showing the manner in which it is removably mounted upon the vertical background panel.

Referring to Fig. 1, the merchandise display assembly there illustrated comprises a pair of supports 10 and 11 arranged at opposite ends of the assembly and adapted to support the assembly in an upright position upon a floor or the like. Each of the support assemblies 10 and 11 comprises an inverted substantially V-shaped frame element 12 having an apex 13, the two legs of each support element being joined adjacent their lower ends by a transversely extending rod 14. The end support elements 10 and 11 are joined by a substantially rectangular frame comprised of three vertically disposed tubular structural members 15, 16 and 17 which, in the present instance, have a hollow, square cross-section. The vertical structural members 15, 16 and 17 are joined respectively at their tops and bottoms by horizontally extending structural elements 18 and 19 which likewise may be of hollow tubular construction with a square cross-section. Each of the vertical structural members 15, 16 and 17 is provided with a forward and rear face 20 and 21, each of which has a double row of vertically elongated and vertically aligned slots 22 therein.

The upright supports 10 and 11 and the rectangular frame just described, comprise a self-supporting upright frame structure upon which the remaining elements of the merchandise display assembly of the present invention may be interchangeably and selectively arranged in a great variety of ways so as to satisfy specific display needs that may exist at a particular time, and in order to permit frequent rearrangement of displays so that the retail store or other establishment in which the present invention is used may be given a fresh and new appearance from time to time.

As illustrated in Fig. 1, the frame of the present display assembly has a pair of panels 25 and 26 removably arranged thereon on its left-hand side, as a pair of

diagonally disposed shelves upon which any of a great variety of merchandise may be attractively displayed. The panels 25 and 26 are of identical construction, as will be later explained, and in the present instance the panel 25 is arranged at a sharper angle with respect to the horizontal than is the panel 26. On the other side of the front of the frame two panels 27 and 28, each of which may be of the same structure as the panels 25 and 26, are respectively arranged as a horizontal shelf and as a vertical background display panel. Above the panel 28 there is a larger panel 29 which completes the background area above the panel 28. Any arrangement of merchandise desired may obviously be supported upon the horizontal shelf 27, and merchandise may be supported in attractive displays upon the vertical background panels 28 and 29 by means of hook assemblies 30, for example, which will presently be described in detail.

Referring now to Fig. 2, it will be seen that the horizontal panel 27 and each of the other panels is comprised of a peripheral rectangular frame comprising a U-shaped longitudinal channel frame member 31 and similar channel-shaped end members 32 which may be joined to the frame member 31 as by welding or the like. The longitudinal frame member 33 opposite the U-shaped channel member 31 of each panel is L-shaped in cross-section (see Fig. 4), one of the cross-sectional legs 34 of this element being longer than the other and being folded over, as at 35, in a manner such that the depth of the frame member 33 is greater than the depth of the opposite longitudinal frame member 31 and the end members 32.

The horizontal shelf represented by the panel 27 is supported at its opposite ends by a pair of brackets 36 (Fig. 2). Each of these brackets comprises a forwardly extending sheet metal body 37 which may be embossed, as at 38, to increase its rigidity. At the inner end of the body 37 there are formed a pair of hooks 39 which are removably received in an adjacent pair of the slots 22 in the forward faces 20 of the upright structural members 16 and 17 of the support assembly. These hooks 39 hook over the lower edges of the slots, as best shown in Fig. 2, and the rear portion of the body 37 of the bracket between the hooks 39 may be struck in opposite directions to provide diverging brace portions 40 and 41 which are adapted to rest against the forward faces 20 of the uprights 16 and 17 to prevent the bracket 36 from wobbling laterally. In order to increase the ability of the bracket 36 to support substantial weights that may be placed upon the horizontal shelf, the brackets may each be provided with a reinforcing member 42 which may be riveted or spot welded, as at 43, to the body 37 of the bracket so that the reinforcing member 42 will extend downwardly below the bracket and its rear edge 44 will rest against the forward face 20 of the upright structural member 16 or 17. The end frame members 32 of the horizontal shelf panel 27 rest upon the respective upper edges 45 of the brackets 36, and the under leg 32a of each of the U-shaped channel end frame elements 32 is provided with a plurality of openings 32b and 32c, one of which receives an upwardly directed hook-shaped projection 46 formed on the forward end of each of the brackets 36. The receipt of these projections 46 in the openings 32b or 32c of the U-shaped end frame members 32 of the horizontal panel 27 prevents both forward and lateral movement of the panel 27 upon the brackets 36. Tilting movement of the panel 27 upon the brackets 36 may be prevented, if desired, by a hook 47 which is welded or otherwise secured upon the upper portion of the body 37 of each bracket 36 adjacent its rear, and each hook 47 is arranged to project upwardly and overhang the frame member 31 of the panel, as best shown in Fig. 2.

The panels 25 and 26, and all other panels which are

arranged as diagonally disposed shelves upon the present assembly, are reversed in the position with respect to the position of the horizontal panel 27. That is, the L-shaped angular longitudinal frame members 33 of the diagonally arranged panels are disposed at the rear of these panels rather than in the forward position, as is the case in the horizontal panel 27. This will best be seen in Figs. 3 and 4, in the former of which the diagonally disposed panel 26 of Fig. 1 has been removed and a vertical background panel 47 has been arranged in its place. Similarly, in Fig. 4, the upright background panels 28 and 29 of Fig. 1 have been removed from their vertical positions and the position of the larger panel 29 has been reversed—top for bottom—and it has been pivoted forwardly to provide a large diagonally disposed shelf.

When the panels are arranged in the diagonal shelf position, as is the case with the panels 25 and 26 in Fig. 1 and the panels 25 and 29 in Fig. 3, the upwardly and rearwardly disposed edges of these panels, comprising the angular longitudinal frame members 33, are each pivotally supported upon laterally turned ends 50 of a pair of upwardly extending hook members 51, each of which is welded or otherwise secured upon a short forwardly extending L-shaped bracket 52 having a pair of hooks 53 formed thereon similar to the hooks 39 provided on the previously described brackets 36. These hooks 53 on the brackets 52 are removably received over the lower edges of a pair of adjacent openings 22 in the upright structural members, as best seen in Fig. 4, and the body of each bracket 52 at its rear end may be struck in opposite directions so as to provide elements 54 and 55 that correspond to the elements 40 and 41 of the brackets 36 and similarly engage the forward faces 20 of the upright structural members to prevent lateral motion of the brackets 52 and their hook members 51 with respect to the uprights.

It will be observed from Figs. 3 and 4 that the lower wall or leg 32a of each of the opposite end frame members 32 of the frame of the panels is cut away adjacent the longitudinal frame member 33 so as to provide notches or openings 32d which permit easy receipt of the frame members 33 upon the upper end portions 50 of the upwardly extending hook members 51. When so received, the diagonal panels are free to be swung forwardly to any angle desired. The desired angle, and thus the angle of the shelf surface provided by these panels, is maintained by pairs of brackets 56 or 57 which differ from each other only as to their length. The brackets 56 and 57 are substantially identical to the construction of the brackets 36, which have previously been described in detail, except that they need not be provided with the hook elements 47 nor with reinforcing members 42 of the brackets 36. The brackets 56 and 57, as best shown in Fig. 4, are each provided with a longitudinally extending body 58 that is provided at its rear end with a pair of hooks 59 that are identical to the hooks 39 provided on the brackets 36 and the hooks 53 provided upon the brackets 52. The hooks 59 of the brackets 56 and 57 are arranged to be received in adjacent openings 20 of the uprights at any selected elevation, and wobbling movement of the brackets 56 and 57 is prevented by oppositely struck projections 60 and 61 which correspond to the similarly struck projections 40 and 41 of the brackets 36 and the projections 54 and 55 of the brackets 52. The outermost ends of the brackets 56 and 57 are provided with upwardly projecting hook elements 62 which are received, along with portions of the outermost ends of the brackets, in one of the openings 32b or 32c provided in the under leg 32a of the opposite end frame members 32 of the frames of the panels, so that the brackets 56 or 57 together with the brackets 52 and their upstanding hook members 51, support the diagonally arranged panels in fixed positions.

The vertical background panels, exemplified by the

panels 28 and 29 in Fig. 1 and by the panel 47 in Fig. 3, are hung freely upon the laterally turned upper arms 50 of the upstanding hook members 51 of additional brackets 52, the channel-shaped frame member 31 of each vertical panel being received over the hook members, as best shown in the lower portion of Fig. 4, so that the vertically disposed panels are safely retained in place. The lower wall or leg 32a of each of the opposite end frame members 32 of the panels is cut out adjacent the longitudinal frame member 31 so as to provide notches 32e permitting easy receipt of the upper ends 50 of the hook members into the channels of the frame members 31. Lateral movement of each vertical panel is prevented by abutment of the extremities of the laterally turned arms 50 of the hook members 51 against the inner surfaces of the end frame members 32 of the panels.

The supporting surface of each of the panels for the present merchandise support assembly is preferably comprised of a sheet of wide mesh screening or expanded metal which may be spot welded or otherwise secured to the frames of the panels. The panels may also be provided with intermediate frame members 70 which extend between the frame members 31 and 33 and may be welded or otherwise secured thereto. In the embodiment shown in the drawing, it will be observed that the smaller panels have only one of these intermediate frame members provided therefor, as shown in panels 25, 26, 27 and 28, whereas the larger panels, exemplified by the panels 29 and 47 are provided with two of these intermediate members.

The open mesh of the screen or expanded metal merchandise supporting surfaces of the panels provides an excellent medium by which the merchandise supporting hook assemblies 30 may be secured to the vertical panels. Each of the merchandise support assemblies 30 comprises a plate 71 having hook-shaped ears 72 turned rearwardly thereon at its upper side edges, and each plate has a forwardly projecting merchandise supporting rod 73 or other supporting device welded or otherwise secured thereon. It will be understood that the plates may be hooked upon the mesh of the vertical panels at any position desired thereon in the manner shown in Figs. 6 and 7.

For the sake of simplicity in illustration and explanation, the various panels have been shown in the drawing as being installed on only one side of the structural upright members 15, 16, and 17. However, it will be appreciated that the vertically aligned slots 22 are provided in the rear faces 21 as well as in the forward faces 20 of the upright structural members so that any desired arrangement of the panels may be mounted simultaneously on the opposite sides of the upright members. Thus, if desired, one side of the present display assembly may have one arrangement of vertical panels, diagonal shelves and horizontal shelves, while the other side may be provided with an entirely different arrangement. In any event, the horizontal shelves in each instance are mounted upon the upright structural members in the manner described above with respect to the panel 27; the diagonally arranged shelves are mounted in the manner described with respect to the representative diagonal panel 25; and all vertically arranged panels are mounted in the same manner as described above with respect to the panel 47 of Fig. 3.

Although the present embodiment of the invention has been shown with only three upright structural members 15, 16 and 17, it will also be understood that any desired number of upright members may be employed in any particular assembly. The upright structural members are preferably equally spaced apart so that all of the panels may be of equal longitudinal length and may differ from each other only in their lateral width. This simplifies the manufacture of the assembly, but still gives to the user a vast choice in the number of display arrangements that may be made with the assembly. It will furthermore be understood that, while the preferred embodiment

ment of the invention is in the form of a self-supporting structure which may be used as an "island" in a store or other commercial establishment, other forms of the invention may be made. For example the upright structural members may be mounted in fixed position upon an existing counter top or, if desired, they may be mounted against a vertical wall within a room so that a great variety of display arrangements may be made along the wall. It will also be understood that each of the interchangeable panels of the present invention may be fabricated of a single sheet of sheet metal, if desired.

The foregoing description has been given for clearness of understanding only and no unnecessary limitations should be understood to be intended thereby, for it will be apparent to those skilled in the art that numerous variations and modifications may be made in the present invention within the spirit and scope of the appended claims.

I claim:

- 20 1. A merchandise display assembly comprising, a plurality of spaced-apart upright structural members each having at least one row of vertically aligned openings provided in its forward face, a plurality of readily interchangeable panel members, and means including a plurality of panel receiving supports removably hooked over the respective lower edges of selected ones of said openings for selectively supporting said panels in depending vertical positions upon said structural members to provide background elements for said merchandise and in forwardly projecting horizontal and diagonal positions upon said structural members so as to provide horizontally and diagonally arranged forwardly projecting display shelves for said merchandise.
- 25 2. A merchandise display assembly comprising, a self-supporting structure adapted to rest upon a floor and including a plurality of upright spaced-apart structural members each having at least one row of vertically aligned openings provided in its forward face, a plurality of readily interchangeable panel members each having a width
- 30 substantially equal to a multiple of the space between a row of said openings in one of said structural members and a row of said openings in an adjacent one of said structural members, and means including a plurality of panel receiving supports removably hooked over the respective lower edges of selected ones of said openings for selectively supporting said panels in depending vertical positions upon said structural members to provide background elements for said merchandise and in forwardly projecting horizontal and diagonal positions upon said structural members so as to provide horizontal and diagonally arranged forwardly projecting display shelves for said merchandise.
- 35 3. A merchandise display assembly comprising, a self-supporting structure adapted to rest upon a floor and including a plurality of upright spaced-apart structural members each having at least one row of vertically aligned openings provided in its forward face, a plurality of readily interchangeable panel members each having a width
- 40 substantially equal to a multiple of the space between a row of said openings in one of said structural members and a row of said openings in an adjacent one of said structural members, and means including a plurality of panel receiving supports removably hooked over the respective lower edges of selected ones of said openings for selectively supporting said panels in depending vertical positions upon said structural members to provide background elements for said merchandise and in forwardly projecting horizontal and diagonal positions upon said structural members so as to provide horizontal and diagonally arranged forwardly projecting display shelves for said merchandise.
- 45 4. A merchandise display assembly comprising, a self-supporting structure adapted to rest upon a floor and including a plurality of upright spaced-apart structural members each having at least one row of vertically aligned openings provided in its forward face, a plurality of readily interchangeable rectangular panel members each having a width substantially equal to a multiple of the space
- 50 between a row of said openings in one of said structural members and a row of said openings in an adjacent one of said structural members, and means including a plurality of panel receiving supports removably hooked over the respective lower edges of selected ones of said openings for selectively supporting certain of said panels in depending vertical positions upon said structural members to provide rectangular background elements for said merchandise and in forwardly projecting horizontal and diagonal positions upon said structural members to provide rectangular horizontally and diagonally arranged forwardly projecting display shelves for said merchandise.
- 55 5. A merchandise display assembly comprising, a self-supporting structure adapted to rest upon a floor and including a plurality of upright spaced-apart structural members each having at least one row of vertically aligned openings provided in its forward face, a plurality of readily interchangeable rectangular panel members each having a width substantially equal to a multiple of the space
- 60 between a row of said openings in one of said structural members and a row of said openings in an adjacent one of said structural members, and means including a plurality of panel receiving supports removably hooked over the respective lower edges of selected ones of said openings for selectively supporting certain of said panels in depending vertical positions upon said structural members to provide rectangular background elements for said merchandise and in forwardly projecting horizontal and diagonal positions upon said structural members to provide rectangular horizontally and diagonally arranged forwardly projecting display shelves for said merchandise.
- 65 6. A merchandise display assembly comprising, a self-supporting structure adapted to rest upon a floor and including a plurality of upright spaced-apart structural members each having at least one row of vertically aligned openings provided in its forward face, a plurality of readily interchangeable rectangular panel members each having a width substantially equal to a multiple of the space
- 70 between a row of said openings in one of said structural members and a row of said openings in an adjacent one of said structural members, and means including a plurality of panel receiving supports removably hooked over the respective lower edges of selected ones of said openings for selectively supporting certain of said panels in depending vertical positions upon said structural members to provide rectangular background elements for said merchandise and in forwardly projecting horizontal and diagonal positions upon said structural members to provide rectangular horizontally and diagonally arranged forwardly projecting display shelves for said merchandise.

75 4. A merchandise display assembly comprising, a self-supporting structure adapted to rest upon a floor and including a plurality of upright spaced-apart structural members each having at least one row of vertically aligned

openings in its forward and rear faces, a plurality of readily interchangeable rectangular panel members each having a width substantially equal to a multiple of the space between a row of said openings in one of said structural members and a row of said openings in an adjacent one of said structural members, a plurality of panel receiving supports removably hooked over the respective lower edges of selected ones of said openings for selectively supporting certain of said panels in depending vertical positions upon said structural members to provide rectangular background elements for said merchandise, and a plurality of brackets removably hooked over the lower edges of others of said openings for supporting others of said panels in horizontal outwardly projecting positions to provide display shelves for said merchandise.

5. A merchandise display assembly comprising, a plurality of spaced-apart upright structural members each having a row of vertically aligned openings provided in its forward face, a plurality of panel receiving supports removably hooked over the respective lower edges of selected ones of said openings, a plurality of readily interchangeable rectangular panel members removably and pivotally mounted adjacent their upper edges directly upon said supports, and a plurality of forwardly extending brackets removably hooked over the lower edges of others of said openings, the outer ends of said brackets engaging only certain of said panels below the location of their pivotal engagement with said supports and respectively retaining said certain panels in outwardly pivoted positions so as to provide diagonally disposed shelves for said merchandise, the remaining ones of said panels pivotally hanging freely upon said supports in vertical positions to provide vertical background elements for said merchandise.

6. A merchandise display assembly comprising, a plurality of spaced-apart upright structural members each having a row of vertically aligned openings provided in its forward face, a plurality of panel receiving supports removably hooked over the respective lower edges of selected ones of said openings, and a plurality of readily removable and interchangeable rectangular panel members removably and pivotally mounted adjacent their upper edges directly upon said supports and hanging freely thereon in vertical positions along said structural members to provide background elements for said merchandise.

7. The combination set forth in claim 6, including means for pivoting certain of said panels in a direction outwardly of said structural members and for retaining the latter of said panels in their pivoted positions to provide shelves for said merchandise.

8. A merchandise display assembly comprising, a plurality of spaced-apart upright structural members each having a row of vertically aligned openings provided in its forward face, a plurality of panel receiving supports removably hooked over the respective lower edges of selected ones of said openings, each of said supports including a laterally extending arm, a plurality of readily interchangeable rectangular panels each having a rectangular peripheral frame including a first longitudinal frame member of U-shaped cross-section extending along a first longitudinal edge of the panel with the open side of the U directed toward the center of the panel, a second longitudinal frame member extending along the opposite longitudinal edge of the panel, and end frame members ex-

tending along opposite end portions of the panel, certain of said panels being freely hung in vertical positions on selected ones of said arms with the arms received within the U-shaped cross-sections of said first longitudinal frame members thereof to retain said panels in said vertical positions and to provide rectangular background elements for said merchandise.

9. A merchandise display assembly comprising, a plurality of spaced-apart upright structural members each having a row of vertically aligned openings provided in its forward face, a plurality of panel receiving supports removably hooked over the respective lower edges of selected ones of said openings, each of said supports including a laterally extending arm, a plurality of readily interchangeable rectangular panels each having a rectangular peripheral frame including a first longitudinal frame member of U-shaped cross-section extending along a first longitudinal edge of the panel with the open side of the U directed toward the center of the panel, a second longitudinal frame member extending along the opposite longitudinal edge of the panel, and end frame members extending along opposite end portions of the panel, certain of said panels being freely hung in vertical positions on selected ones of said arms with the arms received within the U-shaped cross-sections of said first longitudinal frame members thereof to retain said panels in said vertical positions and to provide rectangular background elements for said merchandise, others of said panels being hung with said second longitudinal frame members thereof in pivotal supporting engagement with others of said arms, and forwardly extending brackets on said structural members engaging the end frame members of said last mentioned panels and retaining the same in a forwardly pivoted position with respect to said structural members to provide shelves for said merchandise.

10. The combination set forth in claim 9, wherein said second longitudinal frame member of each of said panels is L-shaped in cross-section and wherein said laterally extending arms of said supports are pivotally received within the crotch of the L in each of said last mentioned group of panels.

11. The combination set forth in claim 9, wherein said end frame members of said panel are U-shaped in cross-section and openings are provided therein for receiving the outermost ends of said brackets.

12. The combination set forth in claim 9, including horizontally and forwardly extending rests removably secured in selected ones of the openings in said structural members and adapted to support additional ones of said panels in horizontal attitudes to provide horizontal shelves for said merchandise.
